UNITED STATES PATENT OFFICE.

THOMAS C. RICHARDS, OF WINSTED, CONNECTICUT.

CURTAIN-CORD TIGHTENER.

SPECIFICATION forming part of Letters Patent No. 233,802, dated October 26, 1880.

Application filed March 26, 1880. (No model.)

To all whom it may concern:

Be it known that I, THOMAS C. RICHARDS, of Winsted, in the county of Litchfield and State of Connecticut, have invented a certain 5 new and useful Improvement in Curtain-Cord Fasteners, of which the following is a specification, reference being had to the accompanying drawings, where—

Figure 1 is a front view of a curtain-cord 10 fastener embodying my improvement. Fig. 2 is a rear view of same. Fig. 3 is a view of same in central longitudinal section on plane denoted by dotted line $x x$, Fig. 1.

The letter a denotes the frame of the fastener, bearing the ratches b . On the faces of these ratches rides the base of the cord-knob c , the base being provided with the catch d , to take into the ratches. The frame a bears the slot e between the ratches, and the base of 15 the cord-knob bears the hooks f and g , projecting through this slot to the rear of the frame. The hook f bears the spring-base f' .

The spring i is of peculiar shape. It is made 20 of sheet metal. It has at the base the curve i' , which, fitting under the hook f , its extreme 25 rear end meanwhile resting on the base f' , and its front end on the back side of the frame a , holds the spring in place without the necessity

of riveting or cutting a hole in the spring. The front end of the spring bears the curve i'' , which causes the spring to ride easily over the small projections left on the back of the frame in casting it, casting being the common 30 method of making such frames. The hook g (by striking upon the spring) prevents the 35 knob from being unduly raised off the frame in adjusting the knob along the ratches.

I refer herein to the part i' as a "curve." One function thereof is to retain the spring in place by its co-operation with the hook f , and 40 any shape given to the spring at this point, whereby it has its support in a base, f' , and upon a hook, f , is an equivalent shape.

I claim as my invention—

The frame a , bearing the ratches b and slot e , the cord-knob bearing the catch d and the hooks f and g and the spring-base f' , and the spring i , bearing at one end on the back of the frame, and bearing at the other end the curve i' , fitting between hook f and base f' , all combined for use substantially as shown and described.

THOS. C. RICHARDS.
